UNITED STATES PATENT OFFICE

172,574

RADISH CUTTER OR SIMILAR ARTICLE

Harold R. Baldwin, Excelsior, Minn.

Application October 13, 1953, Serial No. 27,160

Term of patent 7 years

(Cl. D89—1)

To all whom it may concern:

Be it known that I, Harold R. Baldwin, a citizen of the United States of America, residing at Excelsior, Minnesota, have invented a new, original, and ornamental Design for a Radish Cutter or Similar Article, of which the following is a specification, reference being had to the accompanying drawing, forming a part hereof.

In the drawing:

Fig. 1 is a front elevational view of a radish cutter or similar article embodying my new design;

Fig. 2 is a side elevational view of the same; and

Fig. 3 is a back view of the same.

I claim:

The ornamental design for a radish cutter or similar article, as shown.
